NEEDLE THREADER

Original Filed Nov. 27, 1926

INVENTOR.
John Rozdilski
By Frank Schaefferman

ATTORNEY.

UNITED STATES PATENT OFFICE

JOHN ROZDILSKI, OF MAYFIELD, PENNSYLVANIA, ASSIGNOR OF ONE-HALF TO JOSEPH A. KIEHART, OF MAYFIELD, PENNSYLVANIA

NEEDLE THREADER

Application filed November 27, 1926, Serial No. 151,077. Renewed March 20, 1931.

This invention relates to needle threaders and particularly to novel means whereby a needle threader may be mounted on a needle bar of a sewing machine and held in operative relation to a needle eye in an elevated position where it will be clear of the manipulations attending the sewing operations and yet have a location whereby it can be expeditiously swung into place for threading a needle when that step of the operation is desired.

It is a further object of the invention to provide a mounting for the threader having novel means by which it is attached to the needle bar and including a novel structure whereby a spring which holds the threader elevated or in inoperative position is also applied to the mounting of the threader, a condition which results in a compact, neat structure of comparatively inexpensive and efficient assembly.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, where-
30 in like characters denote corresponding parts in the several views, and in which—

Figure 1 illustrates a view in elevation of a fragment of a needle bar showing a needle and threader embodying the invention applied thereto;

Figure 2 illustrates an enlarged detail view showing the threader in engagement with the thread being applied to a needle;

Figure 3 illustrates a similar view showing the parts in different positions;

Figure 4 illustrates a view on the line 4—4 of Figure 3;

Figure 5 illustrates a view of the device at right angles to that shown in Figure 1 with the threader in operative relation to the needle;

Figure 6 illustrates a plan view of the blank employed in the construction of the threader guide; and

Figure 7 illustrates a horizontal sectional view of the guide.

In these drawings 10 denotes a needle bar which has the usual seat for a needle 11 and a collar 12 encircles the needle bar at its lower end. The collar is held in place by a set screw 13 which is preferably threaded in the collar and bears against the needle and holds it in the seat. The needle, of course, must be properly set with its eye positioned to receive or coact with the threader. The collar has an extension 14 preferably at right angles to the needle bar and this extension is internally threaded to engage the threads of a screw 15. The arm 16 of the threader is oscillatable on the screw between the head of the screw and the end of the extension of the collar and the said arm is of angular formation or it is offset inwardly toward the needle bar in order that the threading instrumentalities may be brought into alignment with the needle. The outer end of the extension has a shoulder 16^a constituting an abutment for the arm when said arm is at the limit of its upward movement where it is held when the threader is not in use. A spring 17 has one end anchored to the collar or part thereof and said spring encircles the extension and has its offset end connected to the arm 16 and the spring is so made and mounted as to operate for returning the arm to the position in which it is shown in Figure 1 and for yieldingly retaining it in that position in order that an operator may by pressing on the arm move it in the direction of the indicator A for carrying the threading instrumentalities into operative relation to the needle. The shoulder is effective to arrest the upward movement of the arm as stated and the arrangement of the parts is compact and of neat appearance.

The means for threading the needle in the present embodiment of the invention includes two guides or jaws 18 and 19 that are carried by the outer end of the arm 16, and a tongue 20 is also carried by the arm and it projects outwardly in a line between the guides 18 and 19 and it is intended to enter the eye of the needle when the guides are engaging opposed surfaces of the needle. The

tongue may have a notch or hook 21 of sufficient depth or size to create a lodgment for thread and when the threader is operated and the guides are caused to assume the position shown in Figure 3, the thread 22 may be applied to the notch or hook of the tongue and when the arm is released, the spring will serve to move the arm outwardly from the needle and the thread will therefore be drawn through the eye of the needle as it is shown in Figure 2, a condition which will result in the completion of the threading operation.

Preferably in the formation of the arm and jaws, they constitute a one-piece structure preferably stamped from metal having the conformation substantially of that shown in Fig. 6. The jaws are then bent at angles to the arm and parallel to each other with a space between them for the tongue 20.

That portion of the arm between the jaws is slit or cut horizontally as shown at 23 and 24, Fig. 6, and the portion 25 of the arm between the cuts is bent inwardly to form a loop 26 for the reception of a shank 27 formed as an integral part of the tongue 20 and this provision permits the tongues to be substituted expeditiously in the threader arm, should they become impaired or worn.

I claim:

1. A needle threader, a mounting adapted to be mounted for oscillation on a needle bar of a sewing machine, said mounting comprising an arm with an angularly disposed and integral extension, a guide member integral with the lower edge of said extension, a guide integral with the upper edge of said extension, one of said guides lying approximately parallel with said extension on one side and the other of said guides lying approximately parallel with the extension on its opposite side, the said extension having slots to form a seat therethrough, a tongue located between the guides and having a thread hook.

2. A needle threading attachment for sewing machines comprising integral sheet metal members which constitute an arm, provided at one end with an apertured offset means for associating the same with a needle bar of a sewing machine, the same having at its opposite end an offset provided with slits for connecting thereto the shank of a thread engaging hook, said slotted offset portion being provided with integral parallel guide members formed integral with the part having therethrough the slits for the shank of the hook.

3. A needle threader for sewing machines, a one-piece sheet metal structure comprising an arm which is offset and apertured at one end for oscillatory engagement with the needle bar of a sewing machine, the opposite end of said arm having an offset portion which is provided with slits therethrough and an offset portion between the slits which offset portion is adapted to maintain in en-

gagement therewith a thread engaging hook, and parallel side wings which form guides which are integral with the slotted portion of the arm, said guides extending beyond the offset portion of the arm.

JOHN ROZDILSKI.
